UNITED STATES PATENT OFFICE

106,466

DESIGN FOR A SCARF

Henry F. Kaplan, Los Angeles, Calif.

Application July 17, 1937, Serial No. 70,513

Term of patent 3½ years

To all whom it may concern:

Be it known that I, Henry F. Kaplan, a citizen of the United States of America, residing in Los Angeles, county of Los Angeles and State of California, have invented a new, original, and ornamental Design for a Scarf, of which the following is a specification, reference being had to the accompanying drawing, forming part thereof.

The figure on the drawing is a plan view of a scarf embodying my new design.

I claim:

The ornamental design for a scarf substantially as shown.

HENRY F. KAPLAN.
